UNITED STATES PATENT OFFICE.

SUMMERS BROWN, OF NEW YORK, N. Y.

PRINTING-MACHINE.

No. 891,980.

Specification of Letters Patent.

Patented June 30, 1908.

Application filed July 9, 1906. Serial No. 325,343.

To all whom it may concern:

Be it known that I, SUMMERS BROWN, a subject of the King of Great Britain, residing at New York, in the county of New York and State of New York, have invented certain new and useful Improvements in Printing-Machines; and I do hereby declare the following to be a full, clear, and exact description of the invention, such as will enable others skilled in the art to which it appertains to make and use the same.

This invention is in part an improvement on my Letters Patent No. 772,337, dated October 18th, 1904, in which the slotted type are held to the cylinder by a series of removable longitudinal rods. The said invention consists chiefly in certain features for improving the general operation of the machine, and especially in means for automatically 20 returning the printing ribbon to about its first position after printing and providing for presenting at will fresh parts of the ribbon for use so that the whole ribbon may be equally worn in its different sections; also 25 in certain other devices hereinafter more particularly set forth and claimed.

In the accompanying drawings, Figure 1 represents a side elevation of a machine embodying my invention; Fig. 2 represents 30 a plan view of the same; Fig. 3 represents an enlarged cross-section of a part of the cylinder taken close to the inner edge of one of the rubber bands C and looking outward; Fig. 4 represents an enlarged detail side elevation 35 of a part of one of the bars D, the proximate parts being shown in cross-section; Fig. 5 represents an enlarged detail side elevation of one of the gudgeons of the printing cylinder, the sprocket wheel fastened thereon being 40 shown in vertical section; Fig. 6 represents a side elevation of a modified form of type having a hole instead of the notch for the rod; Fig. 7 represents an enlarged detail side elevation 45 of a part of one of the rods E and the row of notched type into which it fits, some proximate parts being shown in vertical section.

A designates the frame of the machine; B, the cylinder, having raised annular end-flanges B' and longitudinal grooves b to receive the type, these grooves being like those of the patent aforesaid, except that they are shallower. In juxtaposition to the said end-flanges, the terminal parts of the cylinder are

enlarged in diameter, providing an annular face B², and narrower annular faces B³ of less diameter are next thereto on the inner side.

C designates a pair of rubber bands fitting on the annular faces B² and providing the friction surface for feeding the paper and equalizing the pressure thereon. They also receive under them the projecting integral lugs or end pieces d of a removable bar D, which extends longitudinally of the said cylinder and is shifted around the same at the distance of one groove from the last line of type as the type-setting proceeds, thereby always presenting a space or slot for the insertion of the next line of type.

E designates the longitudinal removable rods, corresponding in number to the lines of type F and fitting into the notches f of the latter or the holes f' of the modified type shown in Fig. 6. In the present instance they are not held by the pressure of the aforesaid rubber bands as in the case of said patent, but their outer ends pass through holes e in the raised part of the cylinder which forms the outer annular face B², and their inner ends fit into sockets e' of the corresponding raised part of the other end of the cylinder. The other end of each rod E is notched, for convenience in drawing it out, and these notches may also be used to receive keys or wedges for locking said rods in place.

By the above described construction and arrangement of the rods and cylinder, the said rods are held more securely and are spaced more accurately apart than when attached by the pressure of the rubber bands.

G designates the table over which the sheets of paper H are fed under the cylinder and between it and the platen roller I. This table is hinged at one point at h, and is drawn upward by a spring J after each depression by the paper-feed-roll K. The action of this spring also compensates for the diminution of the pile of paper as each sheet is withdrawn. To control the upward movement of said table, I employ a stop L, which is a nut, threaded on a screw-rod M and arranged above a plate N, projecting from said table, said plate being perforated to let it slide up and down on said rod. The latter is operated step by step by a pawl O carried by said table and engaging a ratchet wheel O' mounted on a short horizontal relatively fixed shaft O² and carrying a bevel

wheel P, meshing with a bevel wheel P' on the lower end of the said screw-rod, to turn the same. The said pawl and ratchet are constructed and arranged to feed the said nut or stop upward at each stroke a distance corresponding approximately to the thickness of a sheet of paper; so that each depression of said table provides for adjusting the surface to be printed or to the position which it should occupy with respect to the printing cylinder for the next impress. The said paper-feed-roller is mounted on a bifurcated arm K' of a shaft K², provided with a sprocket wheel or equivalent gear Q connected by an endless driving chain or belt Q' to another sprocket wheel Q² of diameter equal to that of Q and fastened to one of the gudgeons B¹ of the cylinder B by a screw q, also by a stud q², of the latter sprocket wheel, fitting into a socket q' of said gudgeon. By removing said screw, the wheel Q² is left free to be removed from the said gudgeon, the said stud being readily pulled out of the socket. A graduated disk R is fast on shaft K² between the two parallel plates of arm K, and is engaged peripherally by a clamping screw R', which passes through the bent outer end of said arm, to lock the said arm in any desired position of pivotal adjustment, thereby regulating the position of the paper feed roller K with regard to the point or line of the paper which it will impress. As the shaft K² and the printing cylinder turn equally and simultaneously, it follows that such adjustment of feed roll and of the part of the sheet at which it begins to operate must correspondingly adjust the printing, shifting the lines of print forward or backward.

S designates the printing ribbon, which passes between the platen roller and the printing cylinder constituting the two members of a printing couple, but not around the latter. Its ends are attached to spring-rollers or spring-barrels T and U of any approved construction normally balancing each other. When the type on the printing roller and platen roller grip the paper and ribbon between them in the act of impressing the former, the pull on said ribbon caused by the rotation of the said cylinder puts extra tension on the spring t of the upper and front spring roller T which is thereby enabled to overcome the spring u of the corresponding roller U, the latter occupying a rearward and lower position. When the last line of type set in the cylinder turns beyond the gripping point, the ribbon is freed and drawn back by roller T to about its first position. There is always such a last line, the cylinder being designedly left with an ungrooved part, which of course bears no type.

The platen or impression roller I is journaled at the ends in pivoted supports or supporting links I' and one of its gudgeons i is extended to receive, beyond the proximate

support, a lever I² pivoted near its middle thereon and having its forward end arranged to bear against the inclined face V⁴ of the upper part of a spring V attached to frame A at its lower end, said spring being adjusted in position by a screw V' entering a screw-threaded socket V² of said frame. On raising the platen roller into operative position and actuating one end of said lever the forward end of the latter will ride down the inclined end of said spring and catch below the said incline, the said lever being then in line with its pivot and the said upper end of the spring and holding the said platen roller as thus placed.

The cylinder B is driven by convenient gearing, for example a large gear wheel W which meshes with a smaller wheel W' on a shaft W² operated in any convenient way. This gear wheel may be engaged at will by a locking stud W³ that passes inward through a part of the frame A. In this way the cylinder may be conveniently locked at any time.

X designates a guide frame bearing for the pile of paper sheets as shown in my Patent #825186, dated July 3d, 1906, and movable therewith up and down on studs X' on the tilting feed table. The latter also bears adjustable guide plates X² for the sides of the paper. This table rests on a box Y, which affords means of attachment for some of the minor parts hereinafter referred to and may also contain loose extra parts and convenient tools.

The operation is as follows: The line of type having been filled side by side into the space or slot formed by the removable bar D the rod E is passed lengthwise in through the hole e and through the alined notches, holes, grooves or other openings of said type and into the socket e'. The said bar is then shifted to the next groove and the typesetting and locking are repeated till the cylinder has received its full supply of type. The platen roller is then lifted and locked in operative position. The cylinder is rotated, the sheet thereby printed, and the stop for the paper-feeding table simultaneously lifted to compensate for the withdrawal of the sheet. The ribbon is retracted as the cylinder turns beyond the gripping point; the sheet falls off; the table and paper are lifted, as described, the thickness of one sheet of paper, and the cycle of operations is repeated.

The two spring rollers T and U may be raised at will out of their bearings and turned to wind the ribbon from one to the other, before replacing them. By thus winding the ribbon more or less forward or backward, a fresh part of it is presented for use and wear. Thus, after using one part of the ribbon to its utmost efficiency, I am enabled to successively present other parts of it for like exhaustive treatment and so practically

use the entire ribbon to the utmost advantage.

As the ribbon does not pass around the cylinder, I am enabled to have free and convenient access to the periphery of the latter at all points not covered by said ribbon and to the type and rods on said cylinder. As the cylinder may easily be turned to present any part of it uppermost, I have access in this way to all of the type, and the correction of any error is made easy.

The nut L is locked against turning by a chain and pin L' or in any other convenient way.

I do not claim in this application either the means for type-holding herein shown and described or the paper-supporting table and coöperating feeding devices. These are covered respectively by two applications Nos. 367681 and 367682 filed as divisions thereof.

Having thus described my invention, what I claim as new and desire to secure by Letters Patent is:

1. In combination with a printing cylinder its platen roller, a pair of spring rollers; a printing ribbon advanced by the grip of said roller and the type of said cylinder and having its ends wound on said spring rollers, in order that said ribbon may be automatically

withdrawn to about its first position after said grip ceases.

2. In combination with a printing roller and its platen roller, a ribbon passing between them, and removable spring rollers, to which the ends are attached, the latter permitting the ribbon to be wound thereon for shifting it from one to the other more or less and thereby presenting a new part of the ribbon for use substantially as set forth.

3. In combination with the platen roller of a printing machine, a pair of supporting links on which the journals of said roller are mounted, a fixed part to which said links are pivoted at their lower ends, a lever distinct from said links but engaging one of said journals to lift said roller, a fixed fulcrum for said lever, a spring having an inclined face for frictional engagement with the end of said lever to hold said roller in its raised position and means for adjusting the tension of said spring as set forth.

In testimony whereof, I have signed my name to this specification in the presence of two subscribing witnesses.

SUMMERS BROWN.
